UNITED STATES PATENT OFFICE

156,465

DECORATIVE LAMP

George Ruskin, Los Angeles, Calif.

Application July 5, 1949, Serial No. 3,707

Term of patent 3½ years

(Cl. D48—20)

To all whom it may concern:

Be it known that I, George Ruskin, a citizen of the United States of America, residing at Los Angeles, county of Los Angeles, and State of California, have invented a new, original, and ornamental Design for a Decorative Lamp, of which the following is a specification, reference being had to the accompanying drawing, forming a part thereof.

Fig. 1 is a side elevational view of a decorative lamp, showing my new design,

Fig. 2 is an elevational view of the lamp with the shade member thereof in vertical section.

Fig. 3 is a horizontal section taken on the line 3—3 of Fig. 1.

I claim:

The ornamental design for a decorative lamp, as shown.

GEORGE RUSKIN.
